UNITED STATES PATENT OFFICE.

FRED E. SEBRING AND HARRY E. MURPHY, OF SEBRING, OHIO.

SAFETY DEPOSIT-BOX FOR HOME USE.

1,263,712.

Specification of Letters Patent. Patented Apr. 23, 1918.

Application filed July 11, 1917. Serial No. 179,812.

To all whom it may concern:

Be it known that we, FRED E. SEBRING and HARRY E. MURPHY, both citizens of the United States, residing at Sebring, in the county of Mahoning and State of Ohio, have invented a new and useful Safety Deposit-Box for Home Use, of which the following is a specification.

Our invention relates to safety deposit boxes, especially designed for home use.

The objects of the present invention are, first, to construct a simple safety deposit box, and one that can be made cheaply; second, to so construct the box that it will be practically dust proof and at the same time protect the contents to a great extent from absolute destruction by fire in many instances; third, to form the index or division leaves of asbestos or other fire proof material.

These objects, together with other objects readily apparent to those skilled in the art, may be attained by the construction illustrated in the accompanying drawings, although the invention may be embodied in other forms, the construction illustrated being chosen by way of example.

In the accompanying drawings:

Figure 1 is a perspective view showing the box open and all contents removed, except the sliding rod and its parts.

Fig. 2 is a section on line 2—2, Fig. 1 showing in addition to Fig. 1 an envelop and index or division leaves in proper position.

Fig. 3 is a section of the box without its contents on line 3—3, Fig. 2.

Fig. 4 is a top view showing a portion of the box and illustrating the smaller compartment.

Fig. 5 is a section of one of the side members showing the preferred way of forming the groove.

Fig. 6 is an enlarged view showing a portion of one of the index or division leaves and its binding strip.

Similar numerals of reference indicate corresponding parts throughout the several figures of the drawings.

The box proper is made up of the bottom 1, the sides 2, the back 3, the fixed cover portion 4, hinged cover 5, front lid 6 and the partition 7. These various parts constitute the box as a unit. For the purpose of fire protection the various parts of the box are made of sheet metal of the proper

gage, and the exposed edges and ends of the sides and partition of the box are provided with the grooves 8 which are preferably formed as shown in Fig. 5, but the particular method of forming the grooves is immaterial, as it is obvious that the grooves may be formed in various ways. The hinged cover 5 and the front lid 6 are provided with the ribs 9. For the purpose of properly closing the box at all points the outer edge of the lid 6 is provided with the groove 10, which is for the purpose of receiving the rib 11 formed upon the cover 5. To the bottom 1 or its equivalent are attached the eye-bolts 12 which are secured in any convenient and well known manner, which eye bolts are for the purpose of carrying and guiding the sliding rod 13, to which sliding rod are attached the openable clip rings or binder hinges 14. To the binder hinges 14 are attached or strung the index or division leaves 15 which are for the purpose of fire protection formed of asbestos or like material and for the purpose of protection against wear or injury, the edges of said index or division leaves are bound with the metal strips 16. In use the proper number of index leaves 15 are strung upon the hinges 14 and when the parts are in their normal position or what might be termed the box is in its closed position, the sliding rod 13 is located in such a position that the box proper can be closed.

When it is desired to remove any letter, memorandum or other paper located between the index leaves the top cover 5 and the front cover 6 are brought into the position illustrated in Fig. 1, after which the sliding rod 13 can be moved endwise, thereby bringing the index leaves 15 forward and their rear portions from under the fixed plate or cover 4, after which, and when in this position the various leaves are free to be turned upon their hinged connection. It will be understood that the outward movement of the rod 13, together with the index leaves 15 and their contents will be limited by reason of the fact that the forward openable hinge 14, which like the rear hinge is securely attached to the rod 13, will strike one of the eye-bolts 12.

For the purpose of providing a device of the character described in which bonds, deeds and the like can be placed, the smaller compartment is provided, which compartment is in this instance to the right of the

division 7, and in which compartment may be placed an asbestos container 17 preferably of the bellows type, said container being made of asbestos or other fire proof material. For the purpose of properly retaining the container in its particular compartment the rear part of the compartment is provided with the spring clip 18, which spring clip is for the purpose of holding the 10 container.

In the drawings, we have illustrated in a conventional way means for locking the box, but no claim is made for any particular way, and hence no description is necessary 15 as it is obvious that any ordinary and well known lock and key may be used.

For the purpose of allowing the front lid 6 to come snugly against the ends of the side members 2 and the partition 7 the bent 20 member in which the groove 10 is located should be cut away as illustrated at 19.

The hinge covers 5 and 6 are connected to the box by suitable hinges such as shown in Fig. 3, the connection being made by 25 means of the rod 20, as illustrated in said figure.

Although the drawings and above specification disclose the best mode in which we have contemplated embodying our invention 3 we desire to be not limited to the details of such disclosure, for in the further practical application of our invention, many changes in form and construction may be made, as circumstances require or experience suggests, without departing from the 35 spirit of the invention, within the scope of the appended claims.

Having fully described our invention

what we claim as new and desire to secure by Letters Patent, is—

1. In a device of the character described, the combination of a box made up of bottom, sides, fixed and hinged cover sections, a partition and a front cover, the ends and edges of the side members and partition 45 provided with grooves, the hinged cover and front lid provided with ribs, said ribs adapted to fit in the grooves of the side members and partition, said box provided with relatively large and small compartments, a sliding rod located in the large compartment, means for guiding said rod and a series of index leaves hinged to said rod.

2. In a device of the character described, 55 the combination of a box formed of sheet metal, said box provided with relatively large and small compartments, the larger compartment provided with a sliding rod, means for guiding said sliding rod, and a 60 series of index leaves hinged to said rod, said series of index leaves formed of refractory material.

3. In a safety deposit box for the purpose described, the combination of a box provided with an index leaf compartment and an envelop compartment, means for holding the index leaves and allowing backward and forward movement thereof and means for limiting the forward movement of said 70 leaves.

In testimony that we claim the above, we have hereunto subscribed our names.

FRED E. SEBRING.
HARRY E. MURPHY.
